TYPE-MAKING MACHINE.

1,326,876.

Specification of Letters Patent. Patented Dec. 30, 1919.

Application filed July 21, 1914. Serial No. 852,324.

To all whom it may concern:

Be it known that I, JOHN T. QUIGLEY, a citizen of the United States, and a resident of Boston, county of Suffolk, and State of Massachusetts, have invented an Improvement in Type-Making Machines, of which the following description, in connection with the accompanying drawings, is a specification, like characters on the drawings representing like parts.

This invention relates to machines for making printing types, and more especially, though not exclusively, to a machine for producing upon a strip of sheet metal or other appropriate material one or more raised characters, which can be utilized to reproduce such characters in connection with an appropriate printing mechanism.

My invention will be best understood by reference to the following specification, when taken in connection with the accompanying drawings of one specific embodiment thereof, while its scope will be more particularly pointed out in the appended claims:

In the drawings:

Figure 1 is a central, longitudinal section, partly in elevation, of a type-making machine embodying my invention;

Fig. 2 is a detail, sectional view on line 2—2 of Fig. 1;

Fig. 3 is a detail, sectional view on line 3—3 of Fig. 1;

Fig. 4 is a sectional view, on line 4—4 of Fig. 1, illustrating the character impressing or embossing mechanism;

Fig. 5 is a plan section on line 5—5 of Fig. 4;

Fig. 6 is a detail, perspective view of the multiple spring detent for holding the slides in fixed position;

Fig. 7 is a sectional view on line 7—7 of Fig. 1, illustrating the forming and ejecting mechanism;

Fig. 8 is a perspective view of a portion of the strip of metal, or other material, from which the type bars are to be formed;

Fig. 9 is a perspective view of one of the completed type bars; and

Fig. 10 is a detail sectional view, on line 10—10 of Fig. 4, illustrating the manner in which the characters are embossed.

Referring to the drawings, and to the embodiment of my invention which I have selected for illustration, I have there shown

a type-bar forming and embossing machine, having a frame comprising a bed 11, which may be provided with supporting legs 12, the bed forming a support for two uprights 13 and 14, herein in the form of yokes having bearings 15 and 16, in which a driving shaft 17 is journaled. The latter may be driven in any appropriate manner, but herein in a driving gear 18, secured thereto, meshes with a driving pinion 19, the latter being secured to a shaft 20. If it is desired to operate the machine manually, the shafting 20 may be provided with a crank 21.

The strip of sheet steel or other appropriate material 22, from which the type bars are to be formed, is herein supplied to the machine in the form of a roll placed in a reel 23, herein comprising a pair of side plates 24, mounted to turn upon a spindle or shaft 25. This reel may be otherwise appropriately mounted, but herein its spindle or shaft is mounted in a pair of supporting arms 26, and the latter are pivoted at 27 upon the frame, in order that the reel with its roll of material may be caused to act as its own brake, to prevent too rapid rotation, the roll of material for this purpose resting directly upon a guide 28 for the strip. As a means for guiding the strip and holding the same against lateral displacement, the guide 28 (see Fig. 2) is provided with a groove or channel 29, whose width corresponds exactly with that of the strip, allowing a slight clearance to permit the same to slide freely.

The strip of material may be fed by any other appropriate means, but herein I have provided feed mechanism comprising a feed slide 30, mounted to reciprocate in appropriate guideways 31. This feed slide herein carries a strip-engaging member, herein in the form of a feed pawl 32. This feed pawl might engage the strip in some other appropriate manner, to impart an intermittent feed movement thereto, but herein the strip is previously provided with a series of perforations 33, and the pawl is provided with a projecting spur or lug 34, adapted to enter each perforation, whereby the forward motion of the slide causes the pawl to interengage with the strip and feed the same forward. Upon the return movement of the slide, however, the pawl automatically becomes disengaged from the strip, by reason of the shape of the lug or spur 34,

whose rear face or edge is inclined forwardly somewhat, as shown in Fig. 1, whereby it will be readily withdrawn simply by this rearward motion. The pawl 5 may be held in engagement with the strip by gravity alone if desired, but I prefer to employ a spring 35, to assist gravity in maintaining such engagement. The feed slide 30 herein receives its reciprocatory movement from a cam 36, to which it is connected by a link 37 and lever 38, the latter carrying a cam roll 39, engaging the cam, which preferably has a closed cam path or groove 40. The lever 38 is herein fulcrumed at 41 on a bracket 42, supported on the bed 11. The stroke which the cam mechanism imparts to the feed slide is equal to, or slightly greater than the distance between two adjacent perforations of the strip, so that at each forward stroke, the latter is fed forward a distance equal to the space between two perforations.

As a means for avoiding accident to the feed mechanism, in the event of accidental stoppage of the feed strip by some obstruction or accident, I have herein provided a cam mechanism with a safety device comprising a spring 43, carried by the cam lever 38, and engaging a pin 44, carried by the link 37, the strength of the spring and the arrangement of the parts being such that, in the normal operation of the machine, the spring is unyielding, and the full working stroke is imparted to the feed slide. If, however, there should be any abnormal resistance to the feeding movement of the strip, the spring will yield and allow the slide to stop, while the cam lever continues its forward movement. The spring 43 may be of any other appropriate form, and otherwise mounted upon the cam lever, but herein is fixedly secured at one end to the lever by a screw 45, and is provided with means of adjustment consisting of a screw 46, passing through the spring and threaded into the lever, whereby the free end of the spring may be caused to bear with a greater or less degree of pressure against the pin 44.

I will now describe the character-applying, impressing, stamping or embossing mechanism, by means of which the printing characters are raised or embossed, or otherwise applied to or impressed upon the strip, by the use of coöperating pairs of dies, which are so arranged that any predetermined character or group of characters may be brought at will to an operating point in alinement with the strip, and simultaneously caused to impress such character, or group of characters, thereon.

The character stamping or embossing mechanism may be of other appropriate construction, but herein comprises a guide block 47, having a guideway for the strip, consisting of a groove 48 (see Fig. 4), whose

side walls are spaced apart sufficiently to guide the strip and provide a working clearance to allow the same to be moved freely in a longitudinal direction. The block 47 is herein provided with a recess 49, extending lengthwise of the same (see Figs. 4 and 5), to receive a series of bars 50, slidably mounted therein and provided respectively with recesses 51, containing bars 52, respectively, interengaging with the bars 50 in such a manner as to be movable longitudinally in unison therewith, and yet capable of relative vertical movement (see Fig. 4). To this end, each bar 52 is made the same length as its respective recess 51, with a proper working clearance, so as to be capable of moving freely in the vertical direction, but held against lengthwise movement with respect to the bar 50 by which it is carried.

The bars 50 may be, and preferably are, provided with handles 53, which may be grasped to facilitate the longitudinal shifting of the bars, and these handles are preferably spread apart at their upper ends (see Fig. 5), to enable each part to be readily grasped without interfering with the others. Each pair of bars 50 and 52 constitutes the members of a pair of dies for embossing the raised characters upon the strip of material to form printing characters. If the characters are to be numerals, each pair of dies will be provided with mating numerals 1 to 9, inclusive, and 0, and correspondingly, if letters of the alphabet are to be embossed, the coöperating die members will be provided with mating letters. In the specific instance shown, four of the five pairs of dies will be provided with numerals and the remaining one with letters, in order that a type bar may be formed with any desired letter of the alphabet, associated with any numeral or group of numerals up to and including a four-figure number. The number of pairs of dies may, of course, be increased without departing from the spirit or scope of the invention. Herein, the upper dies 52 are provided with raised characters 54, and the dies 50 with depressed characters 55, as shown in a conventional manner in Fig. 10, although it will be evident that the dies may be reversed if desired.

As a means for holding the dies normally in spaced relation, so that the strip may be fed between them without interference, any appropriate means may be utilized for lifting the upper set of dies, but herein each lower bar 50 is provided with a pair of springs 56, one at each end of the bar 52, to sustain the latter. When the bars 52 are depressed by some appropriate agency, as for example that which is hereinafter described, the upper and lower dies will be caused to coöperate to press or emboss in

the strip of material any predetermined character or group of characters. When the pressure upon the bars 52 is removed, they will rise by permitting the strip to be fed.

As a means for holding the various pairs of dies in the selected position of adjustment, each bar 50 is herein provided with a series of notches 57, coöperating with a spring 58, which serves as a detent normally holding the slide against lengthwise movement, but permitting such movement upon application of a sufficient amount of force to cause the spring to be forced out of the notch in which it is located. The spacing of the notches will, of course, correspond and be equal to the spacing between the characters upon the dies, there being one notch for each character or pair of characters, so that any selected character or pair of characters may be brought to the working point, and held there during the embossing operation. The springs 58 may be of any other appropriate type, but herein all of them are formed of a single plate (see Fig. 6), having a raised portion 59 provided with a series of slots 60, dividing the same into separate resilient portions, each constituting in effect a separate spring, but having their ends united by flanges 61—61. The springs may be otherwise appropriately mounted in the block 48, but herein the latter is provided with a recess 62, in which the spring is held by an inserted block 63.

As a means for indicating to the operator the character or group of characters at the embossing point at any instant, I have herein provided an indicator comprising a plate 64, having therein a sight aperture 65, through which the operator may view a character or group of characters impressed upon the bars 50 (see Fig. 5), the arrangement of these characters corresponding exactly with the characters on the embossing dies already described. Thus, if the character A alone appears at the aperture, the operator is apprised that the impression taken at that moment will cause the letter A to be impressed upon the strip.

Any other appropriate impression mechanism may be utilized, but herein an impression slide 66, having an inserted hardened block 67 is arranged to depress all of the bars 52 simultaneously, to cause the dies to impress or emboss upon the strip of sheet material at will a predetermined group of printing characters. The impression slide 66 is herein provided with a pair of grooves 68, constituting guideways for a pair of guides in the form of tongues 69, formed on or appropriately secured to housings 70, the latter being attached to the sides of the yokes 13 and 14 (see Figs. 1 and 4).

The impression slide 66 may be reciprocated vertically by any appropriate means,

but herein is connected by an eccentric rod and strap 71 to an eccentric 72, the latter being secured to the driving shaft 17. The eccentric rod may be provided with means of adjustment, herein comprising a right- and left-threaded screw 73, provided with lock-nuts 74 and 75. By this means, the eccentric rod may be lengthened or shortened at will, thereby to vary the strength of the impression.

As a means for severing the strip of material at intervals, I may employ any suitable cutting mechanism as, for example, that which is illustrated, and which comprises upper and lower cutters 76 and 77, the latter being preferably provided with an inclined face 78, the purpose of which will presently appear. The upper cutter 76 is herein secured to a cutter slide 79, provided with a recess 80, which receives the cutter, the latter being secured to the slide by one or more screws 81. As a means for preventing the upper cutter slide from lifting the strip after a piece has been severed therefrom, I have herein provided a guide block 82, having a groove 83 constituting a guideway, in which the strip of material is held by overlying plates 84 (see Fig. 3), herein secured to the guide block by screws 85.

The cutter slide may be reciprocated vertically by any suitable mechanism, such for example as an eccentric rod and strap 86, and an eccentric 87, the latter being secured to the driving shaft 17. The eccentric rod may, if desired, be provided with means of adjustment, herein comprising a right- and left-threaded screw 88, having lock-nuts 89, by means of which the cutter slide may be adjusted, so that the upper cutter will properly coöperate with the lower cutter. The eccentric 87 is set so that the cutter slide is properly timed to cause the strip to be severed contemporaneously with the embossing operation, and both occur in the interval between the feeding operations.

After the strip has been embossed and severed, as already described, the severed piece is next formed with two lateral flanges projecting in a direction opposite to that of the raised characters, and the completed type bar is then ejected from the machine. This may be accomplished by other appropriate means, but herein the piece, after being severed from the strip, is advanced slightly by the action of the inclined surface 78, already referred to, until the forward end of the piece strikes an abutment 90, which limits its forward movement, and it then drops upon two ledges 91, which support it in readiness for the next operation. These ledges, it will be observed by reference to Fig. 7, are separated by a space 92, which corresponds to the width the completed type bar is to have. These ledges

are appropriately formed on, or secured to, a pair of guide lugs 93, separated by a space 94 very slightly greater than the width of the severed piece of the strip, so that the 5 same is accurately held against lateral displacement. A forming block, or plunger, 95 now descends upon the piece, and forces the same through the opening 92, the thickness of the block or plunger being approximately equal to the width of the space 92 10 minus twice the thickness of the strip, so that as the block passes through the opening and forces the piece therethrough, right-angle flanges 96 are formed, and a completed type bar 97 is ejected through the bottom of an outlet opening 98.

The plunger or forming block 95 may be actuated by any suitable mechanism, as for example a vertically reciprocating slide 99, 20 operated by an eccentric rod and strap 100 and eccentric 101. The eccentric rod may be provided with means of adjustment, herein comprising a right and left-threaded screw 102, provided with check nuts 103 25 (see Fig. 1).

The operation of the forming block is preferably so timed that it strikes the piece the instant after it has been severed, so that the operation of forming, cutting and ejecting 30 the piece take place in quick succession, and in fact constitute one continuous operation. It will now be apparent that one completed type bar is formed with each two succeeding impressions of the machine,—that is to say, while one set of characters is being impressed upon the strip at 35 one point, a previously embossed portion is being severed, formed and ejected.

It will be observed that the article produced in this particular instance is a type bar provided with longitudinal flanges and a perforation, and having one or more raised reversed printing characters. It will be remembered that the perforations, or their 40 equivalent, were formed in the strip previous to the introduction of the latter into the machine. There is a particular coaction between the feeding device and the particular form of stock used.

50 Each completed type bar is provided with a perforation, which may be utilized to receive a pin or similar opposing element, for the purpose of longitudinally positioning and securing the type bar, while the longitudinal flanges may be utilized in the transverse positioning of the type bar in the printing machine in which the type bar is intended subsequently to be employed. The flanges also possess the advantage of providing 55 a reinforcement giving rigidity to the type bar, and preventing injury thereto because of distortion.

While I have herein shown and described one specific embodiment of my invention 60 for illustrative purposes, and have disclosed

and discussed in detail the construction and arrangement incidental to one specific application thereof, it is to be understood that the invention is limited neither to the mere details or relative arrangement of parts, nor 70 to its specific embodiment herein shown, but that extensive deviations may be made from the illustrated form or embodiment of the invention, without departing from the principles thereof.

Having thus described my invention, what I claim and desire by Letters Patent to procure is:

1. A machine for manufacturing printing types comprising, in combination, means 80 for embossing raised printing characters upon sheet material, and means for bending the sheet material to form one or more flanges projecting from the face opposite to the raised characters.

2. A machine for manufacturing printing types comprising, in combination, means for embossing raised printing characters upon a strip of sheet material, and means for bending both longitudinal edges of said strip 90 to form flanges projecting in a direction opposite to that of the raised characters.

3. A machine of the class described comprising in combination strip feeding means adapted for interengagement with a strip 95 previously prepared with engaging portions, means for impressing one or more characters in or upon said strip, means for severing said strip at intervals between certain characters or groups of characters and means for 100 bending the strip to form one or more flanges projecting from the face opposite to that on which the characters are impressed.

4. In a machine of the class described, a shaft, means for rotating the shaft, means 105 for feeding stock, a die in the path of the stock, a severing device adjacent the die, a bending device, a cam on the shaft to operate the feeding means and eccentric means on the shaft to operate the die, severing 110 means and bending device.

5. In a machine of the class described, means for embossing a design on sheet material, a severing mechanism to sever that part of the material bearing the design, a 115 bending mechanism comprising a bending die adapted to receive an unfinished article from said severing mechanism by gravity and a co-operating bending die.

6. A machine for manufacturing printing 120 types comprising, in combination, means for embossing raised printing characters upon sheet material, and means for bending the sheet material to form one or more flanges projecting from the face bearing the 125 raised characters.

7. In a machine for forming sheet metal printing plates from a strip of sheet metal having a series of regularly spaced perforations, the combination with feeding 130

mechanism adapted to engage said perforations in succession and feed said strip step by step, of a device for embossing printing characters on the strip, severing mechanism 5 so located with relation to said feeding mechanism and driven coöperatively therewith as to sever successive, embossed portions of said strip lying between said perforations, and die mechanism to form 10 flanges on the severed length.

8. In a machine for forming sheet metal strips with identifying characters embossed thereon, the combination with strip feeding mechanism, of means for embossing raised printing characters upon successive portions of the strip, severing mechanism for severing the successive, embossed portions, and die mechanism adapted to form flanges upon each successive severed length and at 20 the same time expel said length from the line of travel of the strip.

9. In a machine for forming sheet metal strips with identifying characters embossed thereon, the combination with means for feeding a continuous strip of sheet metal, of means for embossing identifying characters on successive portions thereof, means for severing successive portions of the strip, and a die adapted by its movement against 25 the severed length of the strip to form flanges thereon projecting from the opposite face of the strip from that on which the characters are embossed and expel said length at right angles to the line of travel 30 of the strip.

10. A machine for manufacturing printing types, comprising in combination, mechanism for feeding a continuous strip of sheet metal step by step, means for embossing raised printing characters upon successive portions of the strip, means for sev- 40

ering successive portions of said strip, and means for bending the sheet metal to form one or more flanges projecting from the face opposite to the raised characters. 45

11. A machine for manufacturing printing types, comprising in combination, means for feeding a continuous strip of sheet metal, means for embossing raised printing characters on successive portions thereof, 50 means for severing successive portions of the strip, and die mechanism adapted to act subsequently upon successive lengths of the sheet metal to change the form thereof.

12. In a machine for manufacturing sheet 55 metal strips with embossed printing characters thereon, the combination with mechanism for feeding a continuous strip of sheet metal through the machine and simultaneously embossing said printing characters upon successive portions of the strip, and means for bending the sheet metal to form one or more flanges projecting from the face opposite to the raised characters.

13. In a machine for manufacturing sheet 60 metal strips with embossed printing characters thereon, the combination with mechanism for feeding a continuous strip of sheet metal through the machine and simultaneously embossing said printing characters upon successive portions of the strip, 65 means for severing the separately embossed portions of the strip, and means for bending the sheet metal after severance to form 70 one or more flanges thereon. 75

In testimony whereof I have signed my name to this specification in the presence of two subscribing witnesses.

JOHN T. QUIGLEY.
